SWIM SUIT

Jacob Solomon, Forest Hills, N. Y., assignor to
 U. S. Knitwear Corp., New York, N. Y., a corporation of New York

Application December 17, 1938, Serial No. 246,313

9 Claims.

(Cl. 2—67)

This invention relates to swim suits or bathing suits, and more particularly to such suits made for wear by women.

The primary object of my invention is to generally improve bathing suits or swim suits. Many women are dissatisfied with bathing suits because they fail to adequately support and mold the body. In an effort to obtain a snug fit for the sake of trim appearance and for confinement of the body, swim suits have been made of Lastex or like fabrics. It has been found that for swim suits such fabrics should have a stretch of, say, sixty or seventy per cent in order to afford comfort and free bodily movement. Such a fabric is, however, inadequate to change or mold the contours of the body.

A much stiffer fabric having a stretch of only, say, thirty or forty per cent, is much better and will successfully confine the body. However, it is not feasible to make a complete bathing suit out of a fabric having so little stretch. Such a suit would hurt the wearer, and in fact, the seams would probably be torn open in even attempting to draw the suit on. If the suit could be gotten on, there would be insufficient freedom of bodily movement for swimming and athletic purposes.

The primary object of the present invention is to overcome the foregoing difficulties, and to provide a swim suit which on the one hand is comfortable, and on the other hand will successfully help mold the body. The most common complaint is protrusion at the abdomen. In accordance with the present invention, the suit is made of a comparatively readily yieldable fabric, and a supporting panel is secured inside of the suit at the front, this panel being made of a much less yieldable material. The panel may, for example, be a Lastex fabric having only thirty or forty per cent stretch. The area of the panel is comparatively limited, and the panel therefore does not interfere with free exercise. For stouter women or for those desiring additional confinement of the body entirely around the hips, a confining band may be used, this band extending around the inside of the suit. When used in combination with the front panel, as would ordinarily be the case, this confining band extends rearwardly from one side of the panel to the other. The band as well as the panel are made of material which is much less yieldable than the suit. Inasmuch as the band is limited in vertical dimension, it does not prevent the suit from being drawn on the body, and does not prevent free movement thereof. The band and

panel are located well down on the body, preferably below the waist, in order not to interfere with bending and twisting of the body.

In accordance with a further feature and object of the present invention, the suit is preferably lined with a knitted material, for example wool or cotton, or a mixture of both. Such a lining is not new, it having been used already in swim suits, particularly of the lastex type. In the present case, however, the lining has additional advantages in concealing the panel or/and the band, and of increasing the comfort of the wearer by providing a smooth, soft layer of fabric between the supporting members and the body. Moreover, the lining may be used to advantage in helping locate the panel or/and band without interfering with free relative movement of these support parts and the suit, and without marring the exterior of the suit by undesirable lines of stitching. More specifically, while the panel or/and band may be secured to the suit by generally upright seams which are anyway used in the manufacture of the swim suit itself, the top and bottom of the panel and band are preferably free of the suit although they may, if desired, be stitched to the lining. When only a front panel is used in the suit, the lining may be limited to the front of the suit, but when the band is used in addition to the panel, the lining is preferably a full lining extending around the inside of the suit.

To the accomplishment of the foregoing and other more specific objects which will hereinafter appear, my invention consists in the swim suit and support elements and their relation one to the other, as hereinafter are more particularly described in the specification and sought to be defined in the claims. The specification is accompanied by a drawing in which:

Fig. 1 shows a ladies' swim suit in use, and illustrates the approximate location of the support members in the particular example here shown;

Fig. 2 illustrates the appearance of the front of the suit of Fig. 1 when turned inside out;

Fig. 3 is a schematic illustration showing the relation of the parts of a suit having a front panel and lining, when viewed in horizontal section;

Fig. 4 is a schematic illustration showing the relation of the parts of a suit having a front panel and circumferential band, and a full lining, when viewed in horizontal section; and

Fig. 5 schematically shows the relation of the parts at the front of the suit when viewed in vertical section.

Referring to the drawing, and more particularly to Fig. 1, the bathing suit there shown is made up in the main of a front section 12 and side sections 14 which are stitched to the front section 12 at the generally upright seams 16. The side sections 14 extend around the back of the body and are stitched together by means of an upright seam at that point. Thus, referring to Fig. 3, there are three main upright seams, the two front seams 16 and the back seam 18. The suit is completed by appropriate shoulder straps 20 (Fig. 1). When, as in the present case, the breast portions of the suit are to be tailored to provide the desired convexity, this is accomplished by the use of additional pieces of material 22 which are suitably patterned and stitched to the front section 12, as by means of the seams 24.

In accordance with the present invention, the comparatively yieldable material of the suit is reinforced at the abdomen by means of a stiffening panel 26. In most cases this panel is alone sufficient, but in rarer cases where a confinement of the body entirely about the hips is desired, a reinforcing band 28 may be provided, this band extending rearwardly around the inside of the suit from one side of panel 26 to the other.

Referring now to Fig. 3, it will be seen that the panel 26 is disposed within the front section 12 of the suit, and that it is secured to the suit at the upright seams 16. The suit is preferably lined at the front, and in the present case such a lining is schematically indicated at 30, the lining also being secured to the panel 26 and the suit at the seams 16.

The construction of the suit may be further explained with reference to Fig. 2. This illustrates the appearance of the front of the suit when the suit has been turned inside out. The panel is indicated in broken lines at 26. The generally upright seams connecting the front section of the suit with the side sections 14 are indicated at 16. The lining 30 preferably extends all the way from the top of the suit to the bottom. The outer material of the suit is folded over or hemmed, as is indicated at 32 and 34, and is stitched to the lining 30, as by means of zig-zag stitching indicated at 36 and 38. When, as in the present case, the lining is confined to the front of the suit, it is nevertheless extended 45 sidewardly at the breasts, as is indicated by the pieces of lining 40. These are secured to the top of the suit by seams 42 and are secured below the breasts by the seams 44. The pieces of lining 40 may be preliminarily stitched to the main lining 30, as by means of turned seams indicated at 43. A piece of lining is also preferably disposed at the bottom of the suit in the crotch, as is indicated at 46.

The lining conceals the stiffening panel 26 and adds to the opacity of the suit at the front. It also increases the comfort of the wearer. It has an additional function when used in combination with the reinforcing panel, namely the function of helping to properly locate the panel and to keep the same in smoothly spread condition. Specifically, it has already been mentioned that the panel is secured at its side edges to the main body of the suit, this being done at the upright seams 16 which anyway form a part of the suit. The top and bottom edges of the panel are, however, left free of the suit. This is desirable for the sake of appearance in order not to mar the smooth-finished exterior of the suit with seams distinctly outlining the inserted panel. It is also

desirable in operation because, as will later appear, the panel is preferably a much less elastic material than the suit. When the panel is made yieldable as it preferably is, the stretch is in a horizontal or sideward direction. By keeping the panel free of the suit at the top and bottom edges, the suit and panel are relatively self-adjustable and may each stretch in accordance with the best distribution of the fabric and the flesh confined thereby; or differently expressed, the panel may fulfill its supporting function without in any way interfering with the desired smoothly spread appearance of the suit. To hold the panel in vertically spread position and to prevent any possibility of either the top or bottom edge turning inwardly, these edges are stitched to the lining 30. The construction will be clear from Fig. 5, in which it will be seen that the panel 26 is stitched at the top and bottom to the lining 30 by lines of stitching 50 and 52, but is free of the front section 12 of the suit, for the stitching 50, 52 does not pass through the outside of the suit. In actual manufacture, this result is readily obtained by stitching the panel to the lining before the lining is stitched to the suit.

The suit may be made of a variety of materials, but is preferably made of the now popular Lastex materials, such fabrics being made of Lastex or like rubber-cored threads. The stretch of these fabrics is preferably considerable. It should be of the order of sixty or seventy per cent, for although the entire suit is intended to hug the body closely and to have some supporting effect on the same, it is impossible to use a fabric of substantially less stretch, say, thirty or forty per cent. The latter would make it impossible or difficult to draw the suit on the body; the seams would probably be torn open in attempting to put on the suit; and once-on, the suit would be unbearably uncomfortable and would seriously prevent free movement of the body.

No such difficulty, however, arises in using a comparatively inelastic weave for the supporting panel 26. This panel is comparatively small in area, it being localized at the abdomen. It might be made without any stretch, or from material woven of inelastic threads but cut on the bias to provide a slight elasticity. However, it is most desirable to make it of a Lastex fabric much like that used for the suit, except that it need not be made of ornamental design or texture, and is preferably so woven as to have but small stretch, say thirty or forty per cent. The elastic threads run in horizontal direction, so that the material stretches sidewardly, but is substantially inelastic vertically.

The lining may be made of any suitable fabric. Preferably a soft knitted fabric is used. Knit wool is desirable, but in less expensive suits, the lining may be knitted cotton or a mixture of wool and cotton. The knit material is soft, water-absorptive, and is yieldable in all directions, and therefore has no tendency to spoil the fit of the suit about the body.

I have so far described the invention as applied to a swim suit having only a front stiffening panel and a front lining. Referring now to Fig. 4, the stiffening material may be used extending circumferentially entirely around the suit. In the present case there is a band 28 in addition to the panel 26. The band extends rearwardly from one side edge of panel 26 around to the other side edge of the panel. The band may be made of a single piece, or as here illustrated, is made of two pieces secured together at 70

54. The band is preferably left free of the suit except for a connection at the upright rear seam 18. In other words, the supporting inserts are secured to the exterior of the suit at only three 5 points, namely the two front seams 16 and the rear seam 18. These points are selected because the suit is anyway provided with seams at these 10 points. The construction may, of course, be modified when dealing with a suit which has been 15 patterned and assembled in different fashion.

10 The suit of Fig. 4 is preferably provided with a full lining. Thus, the side lining sections 56 are used in addition to the front lining 30. The sections 56 are secured together at a seam 58, but 15 the lining is preferably not secured to the suit at this point. The lining is secured to the suit at the front seams 16, but not at the back seam. All sections of the lining are, of course, secured 20 to the suit at the top and bottom edges of the suit, the edges of the lining being concealed by the folded edges or the hems of the suit.

25 The circumferential band 28 is preferably made of Lastex material of limited stretch, and for simplicity, may be made of the same material as is used for the front panel 26. Similarly, the lining sections 56 may be made of the same material as the front lining 30. The band 28, like the panel 30, is preferably not secured to the suit at its upper and lower edges. The edges may, 30 however, be secured to the lining alone in order to safely hold the band in position.

35 In Fig. 2 I have illustrated the internal appearance of a suit having only a front panel and front lining, but the approximate location of the circumferential band 28 when such a band is employed, has been schematically indicated in dot-and-dash lines at 28'.

40 It will be understood that the construction may be appropriately varied with suits of different design. For example, when trunks are employed separate from a suit top, the upper edge of the band may be secured to the upper edge of the trunks if the trunks are not high, yet may be secured to a lining alone as here described, 45 when the trunks extend to a point substantially higher than the band. On the other hand, the suit may be made more modest with a skirt piece. Freedom of movement at the waist is essential for the bending and twisting attendant 50 upon diving, swimming, and beach exercise. The panel and band are therefore set low on the body and are located generally below the waist. At the same time, they are not carried low enough to interfere with free kicking of the legs.

55 It is believed that the construction, as well as the many advantages of my improved swim suit, will be apparent from the foregoing detailed description thereof. It will also be apparent that while I have shown and described the invention 60 in preferred forms, many changes and modifications may be made in the structure thereof, without departing from the spirit of the invention defined in the following claims.

I claim:

65 1. A ladies' swim suit made of yieldable material to permit free bodily movement, a supporting panel secured inside of said suit at the front, said panel being made of material which is much less yieldable in order to help prevent protrusion 70 at the abdomen, said panel being limited in area in order not to interfere with free movement of the body, and a lining at the front of the suit in order to conceal the aforesaid stiffening panel, said lining extending all the way from the top to 75 the bottom of the suit, the side edges of the panel

being secured together with the side edges of the lining to the suit, the top edges of the panel being secured to the lining alone and being free of the suit.

2. A swim suit made of Lastex or like fabric 5 having considerable stretch in order to permit free bodily movement, a supporting panel made of a Lastex fabric having a much smaller stretch, said panel being secured inside of said suit at the front in order to help prevent protrusion of 10 the abdomen, said panel being limited in area in order not to interfere with free movement of the body, a knit lining at the front of the suit, said lining concealing the aforesaid stiffening panel and extending from the top to the bottom 15 of the suit, the side edges of the panel being secured together with the side edges of the lining to the suit, the top edges of the panel being secured to the lining alone and being free of the suit. 20

3. A ladies' swim suit made of Lastex or like fabric having considerable stretch in order to permit free bodily movement, said suit being made up of a front section and side sections which are joined at the rear, a supporting panel made 25 of a Lastex fabric having a much smaller stretch, said panel being secured inside of said suit at the front in order to help prevent protrusion of the abdomen, said panel being so located and limited in area as not to interfere with free movement 30 of the body, a lining at the front of the suit, said lining concealing the aforesaid stiffening panel and extending from the top to the bottom of the suit, the side edges of the panel being secured together with the side edges of the lining to the 35 suit at the seams joining the front section of the suit to the side sections, the top edges of the panel being secured to the lining alone and being free of the suit. 40

4. A lady's swim suit made of Lastex or like 45 fabric having considerable stretch in order to permit free bodily movement, said suit being made up of a front section and side sections which are joined at the rear, a supporting panel inside said suit at the front, and a confining band extending rearwardly around the inside of the suit from one side of the panel to the other, said panel and band being made up of a Lastex fabric having a much smaller stretch in order to help mold the body, the side edges of the panel being secured 50 at the seams joining the front section of the suit to the side sections. 45

5. A ladies' swim suit made of Lastex or like 55 fabric having considerable stretch in order to permit free bodily movement, said suit being made up of a front section and side sections which are joined at the rear, a supporting panel inside said suit at the front, and a confining band extending rearwardly around the inside of the suit from one side of the panel to the other, said 60 panel and band being made up of a Lastex fabric having a much smaller stretch in order to help mold the body, said panel and band being limited in vertical dimension and being disposed below the waist in order not to interfere with free movement of the body, and a lining at the inside of said suit for concealing the aforesaid panel and band, said lining being secured to the top and bottom of the suit, the side edges of the panel being secured together with the lining to the 70 suit at the seams joining the front section of the suit to the side sections, the top and bottom edges of the panel and band being secured to the lining alone and being free of the suit. 65

6. A ladies' swim suit made of yieldable ma- 75

- terial to permit free bodily movement, a supporting panel secured inside of said suit at the front, said panel being made of material which is much less yieldable in order to help prevent protrusion 5 at the abdomen, said panel being limited in area in order not to interfere with free movement of the body, and a lining at the front of the suit in order to conceal the aforesaid stiffening panel, said lining extending all the way from the top to the bottom 10 of the suit, the side edges of the panel being secured to the suit by generally upright lines of stitching, the top and bottom edges of the panel being secured to the lining alone and being free of the suit.
- 15 7. A swim suit made of Lastex or like fabric having considerable stretch in order to permit free bodily movement, a supporting panel made of a Lastex or like fabric having a much smaller stretch, said panel being secured inside of said suit at the front in order to help prevent protrusion 20 of the abdomen, said panel being limited in area in order not to interfere with free movement of the body, a knit lining at the front of the suit, said lining concealing the aforesaid 25 stiffening panel and extending from the top to the bottom of the suit, the side edges of the panel being secured to the suit by generally upright lines of stitching, the top and bottom edges of the panel being secured to the lining alone and being free of the suit.
- 30 8. A ladies' swim suit made of Lastex or like fabric having considerable stretch in order to permit free bodily movement, a supporting panel made of a Lastex or like fabric having a much smaller stretch, said panel being secured inside of said suit at the front in order to help prevent protrusion 5 at the abdomen, said panel being limited in area in order not to interfere with free movement of the body, a lining at the front of the suit, said lining concealing the aforesaid stiffening panel and extending from the top to the bottom of the suit, the side edges of the panel being secured to the suit by generally upright lines of stitching, the top and bottom edges of the panel being secured to the lining alone and being free of the suit.

made of a Lastex or like fabric having a much smaller stretch, said panel being secured inside of said suit at the front in order to help prevent protrusion of the abdomen, said panel being so located below the waist and limited in area as 5 not to interfere with free movement of the body, a lining at the front of the suit, said lining concealing the aforesaid stiffening panel and extending from the top to the bottom of the suit, the side edges of the panel being secured to the suit 10 by generally upright lines of stitching, the top and bottom edges of the panel being secured to the lining alone and being free of the suit.

9. A ladies' swim suit made of Lastex or like fabric having considerable stretch in order to 15 permit free bodily movement, a supporting panel inside said suit at the front, and a confining band extending rearwardly around the inside of the suit from one side of the panel to the other, said panel and band being made up of a Lastex or like 20 fabric having a much smaller stretch in order to help mold the body, said panel and band being limited in vertical dimension and being disposed below the waist in order not to interfere with free movement of the body, and a lining at the inside 25 of said suit for concealing the aforesaid panel and band, said lining being secured to the top and bottom of the suit, the side edges of the panel being secured to the suit by generally upright lines of stitching, the top and bottom edges of the panel and band being secured to the lining alone and being free of the suit.

JACOB SOLOMON.
